UNITED STATES PATENT OFFICE.

JOHN W. STEDELIN AND GEORGE KLEIN, OF CENTRALIA, ILLINOIS.

MINE-CAR PULLER.

Application filed November 1, 1928. Serial No. 316,594.

The invention relates to cable-winding means designed primarily for pulling mine cars into position to be loaded by a conventional mining and car-loading machine.

5 One aim of the invention is to provide a hollow bumper for the mining and loading machine in which all parts of the cable-winding means are mounted, thereby protecting these parts against foreign matter 10 and providing a structure which economizes greatly in space—an essential item on mining machines which are ordinarily encumbered with as much mechanism as can be accommodated.

15 Another aim is to provide a simple and compact arrangement of parts which may be advantageously and efficiently used and will be long-lived under the rough usage to which necessarily subjected.

20 With the foregoing in view, the invention resides in the novel subject matter, hereinafter described and claimed, description being accomplished by reference to the accompanying drawings.

25 Fig. 1 is a side elevation of a portion of a mining and loading machine embodying the invention.

Fig. 2 is a top plan view with the bumper top removed.

30 Fig. 3 is a longitudinal sectional view of the bumper with the contained parts in elevation.

Fig. 4 is a longitudinal section on line 4—4 of Fig. 2.

35 Fig. 5 is a horizontal section on line 5—5 of Fig. 4.

Figs. 6 and 7 are detail longitudinal sections through the winch and associated parts showing the clutch thrown out and in, respectively.

40 Figs. 8, 9 and 10 are vertical transverse sections on lines 8—8, 9—9 and 10—10 of Fig. 6.

A combined mining and loading machine 45 M is shown embodying a truck T having a horizontally elongated bumper B. This bumper is of hollow form and has an opening O in its front through which a cable C passes. Winding means for this cable 50 are confined within the bumper B and hence

said cable and means may be advantageously used to draw cars into position to be loaded by the machine M. The conventional machine is, as part of its usual equipment, provided with a bumper at the same location 55 as bumper B. By using this hollow bumper B instead of the usual bumper, and confining the cable-winding means within said hollow bumper, we provide the machine with the additional car-pulling equipment and at the same time provide space to accommodate such equipment without unnecessarily encumbering the already complex machine in which practically all available space is utilized at the time of manufacture. Aside 65 from these advantages, mounting of the cable-winding means within the bumper locates such means at the most advantageous position for use whether the cars to be pulled be in line with or laterally of the machine 70 M, and such mounting protects movable parts to a great extent against grit, dust, etc. which necessarily exist in the zone around the machine. Therefore, the mounting of the cable-winding means within the 75 hollow bumper, is of paramount importance. Also, the general relation of parts enabling them to be confined in the limited space within the bumper, is of moment. The preferred relation and construction of parts 80 will be specifically explained with the understanding that within the scope of the invention as claimed, variations may be made.

The rear wall of the bumper B is formed by a channel bar 10 whose upper and lower 85 flanges 11—12 project forwardly. Secured to the lower flange 12 by rivets or the like, is a bottom plate 13 to whose free edges an angle metal bar 14 is riveted or otherwise fastened. Secured at its lower edge to this 90 flange is a front wall 15, end walls 16 being integral with this front wall and secured to flange 14 and bar 10. Brackets 17 are secured to the walls 15—16, and a top plate 18 is fastened to these brackets. 95

Within the bumper B, in end to end relation, are a winch 19 and an electric motor 20. The motor shaft 21 is provided at its outer end with a pinion 22 meshing with a gear 23 on a shaft 24 which is mounted in 100

bearings, 25, said shaft being disposed at one side of the motor 20. Preferably, the bearings 25 are secured to a vertical plate 26 which is fastened to the motor housing. The inner end of shaft 24 carries a pinion 27 meshing with a gear 28 on the inner end of a relatively large shaft 29. This shaft 29 extends into the winch 19 and a clutch is provided within said winch for connecting and disconnecting said shaft and winch at will. A spring-contracted brake band 30 preferably surrounds a brake drum 31 on the winch merely to exert a drag thereon when pulling the cable C out for connection with a car.

The shaft 29 is rotatably mounted in two spaced bearings 32—33 which are secured to the bumper bottom 13, and this shaft is shouldered at 34 to abut these bearings and prevent endwise shifting of said shaft. A central bore 35 is formed in the shaft 29 from its outer end to a point near its inner end, and opposed slots 36 extend from the inner end of said bore to the periphery of the shaft. A rod 37 is slidable in the bore 35, a clutch sleeve 38 is splined on the shaft 29 at the inner end of the bearing 32, and a pin or key 39 passes through said slots, sleeve and rod to connect the two latter. The sleeve 38 occupies one end portion of a bore 40 formed centrally in the winch 19, and the remainder of this bore 40 is occupied by a fixed clutch sleeve 41, the two sleeves being provided with co-acting clutch teeth 42. Sleeve 41 is secured in the bore 40 and acts as a bushing rotatably surrounding the shaft 29 to form a bearing for the winch.

Swiveled upon the outer end of rod 37, is a collar 45 to which an angular lever 46 is pivoted. This lever is fulcrumed at 47 to the bearing 33 and extends to the exterior of the bumper B. By preference, flange 11 is depressed at 48 to provide a space under the bumper top 18, through which the lever 46 passes.

By properly shifting the lever 46, sleeve 38 is separated from sleeve 41, permitting the cable C to be unwound from the winch 19 and connected with a car. Then, when the motor 20 is operated to drive the shaft 29, and lever 46 is moved to inter-engage the clutch teeth 42, the winch will be forcibly rotated to wind the cable and pull the car to loading position.

From the foregoing, it will be seen that unique provision has been made for attaining the desired ends. Attention is again invited to the fact that variations may be made, and moreover, it will be understood that the invention is not necessarily restricted to use with mining machinery.

We claim:—

1. A hollow horizontally elongated truck bumper having a cable-receiving opening in its front, a winch mounted in one end of

said bumper and having its axis disposed longitudinally of said bumper, an electric motor mounted in the other end of the bumper and having its axis disposed longitudinally thereof, driving connections between said motor and said winch embodying a clutch within the winch, and a control for said clutch extending to the exterior of the bumper.

2. A hollow horizontally elongated truck bumper having an opening in its front, a winch and an electric motor mounted in said bumper in end to end relation, a horizontal shaft extending rotatably into the winch and having a gear between said winch and the motor, a clutch within said winch for connecting it with said shaft, a second shaft mounted horizontally at one side of said motor, the inner end of said second shaft being provided with a pinion meshing with the aforesaid gear, driving gearing connecting the outer end of said second shaft with the motor shaft, and control means for the aforesaid clutch extending to the exterior of said bumper.

3. A cable-winding mechanism comprising two spaced bearings, a shaft rotatably mounted in said bearings, said shaft having a central bore from one end to a point near its other end and being formed also with a slot from said bore to its periphery, a clutch sleeve at the inner end of one of said bearings slidably surrounding the slotted shaft portion, said sleeve having teeth at its inner end, a rod slidable in said bore, a pin passing through said rod, said slot and said sleeve and connecting said rod and sleeve, a winch between said bearings having a central bore in which said shaft and said sleeve are received, a second clutch sleeve secured within the portion of said winch bore unoccupied by the first named sleeve and contacting rotatably with said shaft to rotatably mount said winch on said shaft, said second clutch sleeve having teeth at its inner end for co-action with those aforesaid, and means connected with the outer end of said rod for shifting the latter to control engagement of the teeth of the two sleeves.

In testimony whereof we have hereunto affixed our signatures.

JOHN W. STEDELIN.

GEORGE KLEIN.
